DESIGN FOR A TIRE

William Edward Hardeman, Birmingham, and Leonard John Lambourn, Erdington, Birmingham, England, assignors to Dunlop Tire and Rubber Corporation, Buffalo, N. Y., a corporation of New York

Application September 14, 1937, Serial No. 71,608
In Great Britain April 5, 1937

Term of patent 14 years

To all whom it may concern:

Be it known that we, William Edward Hardeman and Leonard John Lambourn, subjects of the King of Great Britain, residing at Acocks Green, city of Birmingham, county of Warwick, England, and Erdington, city of Birmingham, county of Warwick, England, respectively, have invented a new, original, and ornamental Design for a Tire, of which the following is a specifica-

tion, reference being had to the accompanying drawing, forming a part thereof.

Fig. 1 is a prespective view, and Fig. 2 is a plan view of a section of a tire showing our new design.

We claim:

The ornamental design for a tire as shown.

WILLIAM EDWARD HARDEMAN.
